CALUTRON

William E. Parkins, Los Angeles, Calif., assignor to the United States of America as represented by the United States Atomic Energy Commission

Application July 23, 1946, Serial No. 685,645

10 Claims. (Cl. 250—41.9)

This invention relates to magnetic devices for moving mechanical elements, and the invention is illustrated herein as applied to a device, known as a "calutron," for separating isotopes on a scale yielding commercially useful quantities of the separated material. For a complete disclosure of a calutron and its mode of operation, reference is made to U.S. Patent No. 2,709,222 which issued to Ernest O. Lawrence, on May 24, 1955, for "Methods of and Apparatus for Separating Materials."

As disclosed in the above-mentioned Lawrence patent, a presently preferred form of the calutron comprises an evacuated tank disposed between the poles of an electromagnet so that the evacuated space within the tank is pervaded with a substantially uniform magnetic field of high flux density. Within the tank, there is provided a "source unit" adapted to project a beam of positive ions of a polyisotopic charge material along an arcuate path extending transversely through the magnetic field, whereby the paths of ions of different mass are caused to diverge toward respective foci disposed 180° along the arcuate beam path from the source unit. A "receiver," also disposed within the tank, is positioned at the 180° foci of the streams of ions of different isotopes for separately collecting the component particles of one or more of those streams.

The receiver of the calutron comprises a viewing face disposed in the path of the beam for defining a separate beam delimiting slot for each ion stream from which the collection of material is desired, each such slot being adapted to pass a delimited portion of the beam enriched with respect to a particular isotope component; and a separate ion collecting pocket is disposed behind each such slot for receiving and retaining the particles passing therethrough.

The principal components of a calutron ion beam form a wide, ribbon-like stream of particles, the stream being relatively thin where it leaves the source unit, gradually increasing in thickness during the first 90° of its arcuate travel, and then decreasing in thickness during the second 90° of its arcuate travel. The final thickness of the beam at the 180° region of focus is substantially greater than the thickness at the source unit, by virtue of the angle of divergence of ions of the same mass at the source unit and the normal divergence of streams of ions of different mass.

The principal components of the ion beam comprise particles of appreciable mass that are caused to deviate very slightly from true arcuate paths by various electrical and magnetic conditions within the calutron tank, which conditions cannot readily be completely controlled in practice. In addition, slight irregularities in the operation of a source unit are difficult to prevent and, as a result, the ion output of the source unit tends to fluctuate slightly during its operation.

All of these abnormal conditions affect the orientation of the 180° focal patterns of the beam, which should remain focused as accurately as possible upon their respective beam receiving areas on the beam viewing face of the receiver. More particularly, as a result of certain types of abnormal conditions, the ribbon-like beam has been observed to twist or precess slightly in one direction or the other about a median path of the beam, thereby causing the 180° focal patterns to rotate to the same extent about respective axes, passing approximately through the geometrical centers of the focal patterns in the direction of travel of the beam at the 180° region of focus. Such twisting or precession of the beam destroys the accuracy of focus of the focal patterns on their respective beam receiving areas of the receiver, which reduces the amount of material received, or causes excessive contamination of that material arriving at one of the beam receiving areas with material that should arrive at a different beam receiving area.

Accordingly, it is an object of the present invention to provide, in a calutron, apparatus for moving the receiver so that the beam receiving areas thereof follow the shifting of the foci of the beam.

More particularly, it is an object of the invention to provide apparatus that is responsive to the shifting of the foci of a calutron ion beam for automatically moving the receiver so as to maintain a proper focus of the beam thereon during operation of the calutron.

Still other objects and advantages of the invention, and the manner in which the desired ends may be accomplished, will appear from the following description of the invention, taken in conjunction with the accompanying drawings, in which:

Figure 1 is a perspective view of a calutron tank having certain wall portions thereof broken away to disclose the arrangement therein of a source unit and a receiver, and the manner in which a beam travels through the tank from the source unit to the receiver;

Fig. 2 is a vertical sectional view of the receiver shown in Fig. 1, illustrating the manner in which the receiver is rotatably mounted on a supporting tube; and

Fig. 3 is an elevational view of the receiver shown in Fig. 1, looking at the beam viewing face thereof and showing how the receiver rotates to follow the shifting of the beam received thereby.

Referring now to the drawings, a calutron tank 11 is shown with part of its defining walls broken away to expose the apparatus contained therein. The tank is mounted between a pair of vertically spaced-apart pole faces 12 (only one being shown) of an electromagnet to maintain a magnetic field of high flux density directed upwardly throughout the interior of the tank from one pole face of the magnet to the other. A source unit 13 is mounted on a wall of the tank at one end thereof for projecting a beam of positively charged ions of a polyisotopic material transversely through the magnetic field along an arcuate path toward an ion receiver 14 mounted on the same wall of the tank at the opposite end thereof. The receiver is rotatably supported by means of a bearing 16 on a tube 17 that projects through a suitable seal 18 in the wall of the tank on which the receiver is mounted, whereby the receiver may be rotated about the axis of the tube 17 and the tube may be axially moved to position the receiver properly with respect to the beam to be received thereby.

The beam transmitted from the source unit 13 is of the type hereinbefore described comprising separate streams of ions of different isotopes (the streams overlap to a considerable extent), the beam having a uniform, substantial height or width from end to end but varying in thickness. At the receiver, the beam components, by virtue of their divergence during travel from the source unit, have combined focal patterns that spread over a considerable area of a viewing face 19 of the receiver.

Slots 21 and 22 may be provided in the viewing face 19 for admitting into the interior of the receiver selected portions of two of the isotope ion streams. In the present instance, employing a suitable uranium charge material in the source unit 13, the beam may be focused on the receiver 14 so that a selected portion of maximum intensity of the stream of U^{235} ions will pass through the slot 21 and a selected portion of maximum intensity of the stream of U^{238} ions will pass through the slot 22. Since the U^{238} portion of the beam is by far the most intense portion, it is employed in the manner described hereinafter for actuating a receiver aligning mechanism to maintain alignment of the receiver with the beam when the beam twists in the manner described above. The vertical axis of this portion of the beam, at all points along its length, is schematically illustrated in Fig. 1 by an arcuately curved surface 23 extending from the source unit 13 to the slot 22 in the receiver viewing face. In other words, the arcuately curved surface 23 represents the locus of U^{238} ion paths that lie on the vertical or major axis of the beam from end to end thereof.

Referring now to Fig. 3, the vertical axis of the U^{238} portion of the beam at the receiver is represented by the line 26. Because of the tendency of the beam to rotate or twist about a median path thereof, the vertical axis of the beam tends to twist in one direction or the other to a position such as is represented by the line 26a. When this occurs, it is necessary to rotate the receiver about the axis of the tube 17 in order to maintain alignment of the slots 21 and 22 with the foci of the U^{235} and U^{238} components of the beam, respectively. To effect such movement of the receiver automatically, a device such as the one now to be described, is mounted on the receiver in the path of the beam and in the magnetic field pervading the interior of the tank for cooperating with the U^{238} portion of the beam to rotate the receiver in response to twisting or shifting of the beam.

Four somewhat elongated pieces of magnetically permeable material 27 are rigidly secured to the viewing face 19 of the receiver in any suitable manner for rotation therewith about the axis of the supporting tube 17. These magnetic pieces are disposed symmetrically with respect to the U^{238} slot 22 with the magnetic axes of each pair of diagonally opposite pieces aligned, and with diagonal lines 28 defined by the axes of the magnetic pieces intersecting directly in front of the geometrical center of the U^{238} slot. The material from which the magnetic pieces are made should be one having a high magnetic permeability that drops sharply at a predetermined elevated temperature, such as Kovar (a well known, substantially carbon-free alloy of iron, cobalt, and nickel); and the pieces should be so located that they are normally heated by the beam to temperatures slightly below the critical temperature at which they lose their magnetic permeability.

By properly selecting the size of the magnetic pieces 27 with respect to the intensity of the portions of the beam by which they will normally be bombarded (determined by their positions on the viewing face 19 and the various characteristics of the beam), it is possible to create a condition of magnetic equilibrium when the vertical axis of the U^{238} slot is accurately aligned with the vertical or major axis 26 of the U^{238} portion of the beam at the receiver. If the beam twists so as to bring its vertical axis to the position indicated by the line 26a, it is apparent that a diagonally opposite pair of magnetic pieces 27 will be subjected to stronger than normal ion bombardment and that the temperature of this pair of magnetic pieces will be raised accordingly. When the temperature of this pair of magnetic pieces rises above the critical value referred to, the magnetic permeability of these pieces will drop, thereby upsetting the condition of magnetic equilibrium. The entire receiver will then be caused to rotate about the tube 17 in a direction to bring the other pair of diagonally opposite magnetic pieces 27 more

nearly into alignment with the calutron magnetic field. Such rotation of the receiver moves the magnetic pieces toward positions of symmetry with respect to the shifted major axis of the beam, thereby eliminating the condition that caused excessive heating of one pair of magnetic pieces. As long as the beam remains in its twisted position, any tendency for the receiver to rotate back to its normal position will cause the above described condition of normal heating of the magnetic pieces to reoccur, thereby counteracting such tendency. While the arrangement may be inclined to oscillate back and forth somewhat before reaching a new position of equilibrium appropriate for reception of the twisted beam, the new position of equilibrium will be reached in a reasonably short time.

From the foregoing description, it will be appreciated that I have provided means for moving a receiver automatically to maintain the beam receiving areas thereof in alignment with the foci of a calutron ion beam as the beam twists about a median path thereof. However, it is to be understood that the invention is not limited to the particular apparatus or to the particular type of use disclosed herein, but is applicable to a variety of similar problems. Accordingly, the true spirit and scope of the invention is intended to be coextensive with the terms of the appended claims.

What is claimed is:

1. In apparatus including a target and means for projecting a ribbon-like beam of charged particles toward the target, said beam being characterized by a tendency to precess and thereby to shift out of focus with the target; means associated with the target and responsive to the precession of the beam for effecting a corresponding rotation of the target.

2. Apparatus as defined in claim 1 including means mounting said rotatable target for movement substantially tangentially of said beam path.

3. In apparatus including a movable target and means for projecting a ribbon-like beam of charged particles toward the target, said beam being characterized by a tendency to precess and thereby to shift out of focus with the target; means mounted on the target in the path of the beam and responsive to the precession of the beam for effecting a corresponding rotation of the target.

4. In apparatus including a magnetic field, a target disposed in said magnetic field, and means for projecting a ribbon-like beam of charged particles through said magnetic field toward said target, said beam being characterized by a tendency to precess and thereby to shift out of focus with the target; means mounted on the target and operative in response to the precession of the beam for cooperating with the magnetic field to effect a corresponding rotation of the target.

5. In apparatus including a magnetic field, means for projecting a beam of charged particles through said magnetic field, and an element to be rotated in response to changing beam conditions; means mounted in the path of said beam and operative in response to changing beam conditions for rotating said element.

6. In apparatus including a magnetic field, means for projecting a beam of charged particles through said magnetic field, and an element to be rotated in response to changing beam conditions; means mounted in the path of the beam and operative in response to changing beam conditions for cooperating with the magnetic field to effect rotation of said element.

7. In apparatus including a magnetic field, means for projecting a beam of charged particles through said magnetic field, and an element to be rotated in response to changing beam conditions; a member affixed to said element and having a normally high magnetic permeability that drops sharply at a predetermined elevated temperature, said member being mounted in the path of the beam within said magnetic field for movement along

a predetermined path under the influence of said magnetic field when the magnetic permeability of the member changes.

8. In apparatus including a magnetic field, a target disposed in said magnetic field, and means for projecting a ribbon-like beam of charged particles through said magnetic field toward said target, said beam being characterized by a tendency to precess and thereby to shift out of focus with the target; means disposed in the path of the beam and subject to heating at a rate dependent upon the position of the beam with respect thereto, said means being operative in response to variation in its temperature for rotating the target to compensate for shifting of the beam.

9. Apparatus as defined in claim 8 wherein said means subject to heating by said beam comprises a plurality of metallic pieces arranged in spaced relation upon one face of said target.

10. In apparatus including a magnetic field, a target disposed in said magnetic field, and means for projecting a ribbon-like beam of charged particles through said magnetic field toward said target, said beam being characterized by a tendency to precess and thereby to shift out of focus with the target; means disposed within said magnetic field and in the path of the beam and subject to heating at a rate dependent upon the position of the beam with respect thereto, said means being operative in response to changes in its temperature for cooperating with said magnetic field to maintain the target in focus with the beam as it precesses.
